CARD HOLDER ACTUATED TIME RECORDER

Philipp Vannini, Zug, Switzerland, assignor to
 Landis & Gyr, A. G., Zug, Switzerland, a corporation of Switzerland

Application February 19, 1945, Serial No. 578,699
 In Switzerland August 18, 1944

11 Claims. (Cl. 346—78)

In the present-day designs of workmen's time recorders, the tendency has been to devise constructions rendering possible the operation of the machine by a single hand of the operator so as to simplify the construction and reduce the number of working parts of the machine. Such recorders have been made, for example, with a special actuating member located adjacent to the card holder so that the card may be inserted and said member operated at the same time by one and the same hand of the operator without releasing the card. The use of a special mechanical actuating member, however, in recorders as heretofore constructed, has not satisfactorily brought about a desirable simplification of the machine. Other types of machines, having the same idea in view, have employed electrical means for initiating a printing action when a card is inserted in the card holder, the card closing a contact bringing into action an electromagnet causing the record to be made. Such devices, however, are comparatively expensive of construction and, as they depend upon the use of electric energy, any interruption of the current renders the apparatus inoperative.

The present invention is designed to overcome these objections and one of its objects is to provide a simplified type of machine in which use is made of the card holder itself as an actuating member, whereby the necessity of employing a separate and special form of actuating device is avoided.

Another object of the invention is to provide means whereby the card holder may be used to release itself for a temporary lateral shift from a set printing position, whenever such a shift is found to be necessary, without disturbing any of the automatic working parts of the machine.

Still another object is to provide a machine of simplified construction in which the printing mechanism is adapted to be mechanically operated while governed for timed printing by suitable clockwork or other suitable timing means.

Other objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

Figure 1 of the accompanying drawing shows by way of example in perspective view, with parts broken away and in section, one form of con-

struction for carrying my invention into practical use, and Figure 2 shows a detailed side elevation of a detent.

In the casing 1 of the recorder there is arranged a card holder or chute 2 having at its upper end a mouthpiece 3 for the insertion and removal of the workmen's time cards. This mouthpiece 3 projects outward through a slot 4 of a size to permit the card holder to be rocked either forward or backward from a normal position, as hereinafter described, and the mouthpiece is formed so as to adapt it to be grasped by the hand of the workman inserting the card and used on the insertion of the card as a handle to rock the card holder and set a time recording printing mechanism into action. The cardholder 2 is supported by apertured ears or bosses 5 oscillatable on a horizontal transverse shaft 6, to adapt it to be shifted laterally in the usual way for in and out time checking (workmen's entering and leaving the shop) operations, by means of a crank 7, which crank extends through and operates in a vertical slot 9 in the lower portion of the card holder.

The printing type wheels 8, of a printing mechanism driven from clock 8' are arranged at the top of the casing in front of the cardholder, and disposed between the same and the cardholder is an ink ribbon 10 arranged in line with a slot 11 in the holder. At the rear of the cardholder, in line with the wheels 8, ribbon 10 and slot 11, is the printing head 12 of the printing striker or hammer which includes a spring metal strip or shank 13 which is fixed to the upper vertical arm of a T-shaped striker lever 14 pivotally carried by a shaft 15. This lever has a rearwardly extending arm, bearing on a curved free portion of a leaf spring 16 fixed at one end to the casing, and a downwardly projecting arm fixed to a latch bar 17 engageable by a hooked latch member 18 secured to the cardholder at 18a. The cardholder is connected at its upper end to the rear wall of the casing by a coiled spring 19, and secured at one end to said wall, below the level of the spring 19, is a leaf spring 20 against which bears an arm 21 on the cardholder, said spring 20 being limited in its forward movement by a stop 22. Another arm or lug 48 located on the cardholder above the arm 21, bears on the spring shank 13 of the hammer or striker. The cardholder 2 has a normal vertical position shown in the drawing, from which it is adapted to be swung forward to printing position for cooperation with the wheels 8 and ribbon 10. Spring 19 returns the cardholder to this normal position when the

cardholder is released by the operator after it has been manually moved forward to printing position. In the normal position of the cardholder the springs 13 and 16 are held under tension, and spring 20 is also held under slight tension, by pressure of the members 48 and 21, and the hammer is thus placed in a condition to be spring impelled for a printing action when the cardholder is moved forward to printing position and in such movement releases the latch 18 and frees the hammer for action. Spring 20 normally opposes movement of the cardholder in a rearward direction from its normal position but permits rearward movement of the cardholder for a special operation, as hereinafter described. The slot 4 is of suitable length transversely of the casing to allow the cardholder to be shifted laterally to change its position for in and out (for example, a. m. and p. m. time) printing operations, and the slot is of sufficient depth from front to rear to allow the cardholder to be rocked both forwardly and rearwardly from its normal position.

A pivoted latch 23 is provided on the holder for locking it in its laterally shifted positions. This latch is engageable with spaced keeper notches in a stationary latch bar 24. The latch 23 is tilttable vertically into and out of locking position and is held by gravity in locking position. A pivoted vertically tilttable releasing bar 26 is provided to control the latch and is operated at proper time periods from the clockwork mechanism by means of a control or trip rod 27 actuatable in timed accord with the crank 1. A lug 25 on the latch 23 has a beveled (see Fig. 2) face normally bearing on the front face of the bar 26. When the cardholder is shifted rearward manually this beveled face of the latch will ride upon the bar 26 to lift the latch out of the notch in the bar 24 with which it has been engaged. By this action the latch may be retracted independent of the time controlled mechanism to allow the cardholder to be laterally shifted manually for a special time checking operation, as, for example, an out printing operation during an in time printing period.

In a guide slot 28 in the cardholder a feeler or card operated trip member 29 is fitted to slide vertically and so as to be depressed by a card inserted downward through the mouthpiece 3. The feeler has a downwardly projecting arm 30 pivoted at 30' to the free end of the horizontal arm 31 of a bell-crank latch lever having a vertical upwardly projecting latch arm 32. At the angle of intersection of its arms 31, 32 the latch lever is pivoted as at 33 to the outer end of a supporting arm 34 of a vertically movable setting and trip slide 34 mounted as at 34', at the lower end of the cardholder. This slide carries at its upper end a pin 41 engaging a short vertical slot 42 in the end of the lever arm 31 pivoted to the arm 30, thus forming a lost-motion or slip-joint connection between the parts 30, 31 and 34. The slide 34 is adapted to be adjusted through a rod 35, actuated by the clockwork mechanism to set the feeler 29 at different card engaging positions relative to the slot 11 for different day-time marking periods, and to correspondingly set the lever 31, 32 for control actions. A spring 40 carried by arm 34' engages the arm 31 to hold said arm 31 elevated and arm 32 in a latching position in which pin 41 is engaged by the lower end wall of the slot 42, whereby the feeler is supported in its set working position while its downward

movement is permitted under pressure of an inserted card against the tension of spring 40, and whereby, when the feeler is depressed, lever 31, 32 will be operated for a releasing action.

Fixed to the card holder is a sleeve 38 having a longitudinal slot 43 therein through which projects a pin 44 fixed to the shaft 6. By this construction the cardholder is mounted to shift laterally on the shaft but coupled to the shaft to rock therewith. A bar 37 has an eye 37a at its lower end which loosely engages a reduced end 38' of the sleeve 38 and is held thereon by a collar 37' fixed to said reduced end of the sleeve, the upper end of the bar being forked at 38' to slidably engage a stationary guide bar 33, whereby the bar is fitted to slide with the sleeve but held from rotation therewith. In the absence of a card in cardholder 2, bar 37 is engaged by a laterally bent detent finger 36 at the upper end of the lever arm 32 to lock the shaft and the cardholder from rocking movement forwardly from and to the normal position of the cardholder. The arm 32 swings on pivot 33 to move the detent 36 into locking position behind the arm 37 and to withdraw it therefrom.

A guard plate 49 is mounted to shift with the cardholder and cover the slot 4 at all times. This plate may be provided with scale marks for co-operation with a pointer 50 to indicate the lateral shift positions of the cardholder and to guide a workman in marking a manual shift for the special checking out marking of the workman's card.

An arm 45 may be mounted on the shaft and carry a pawl 46 for engagement with a toothed wheel 47 operative when the shaft is rocked to impart a shifting movement to the ribbon 18, through gearing 47' and spool 47'' or to rewind the driving spring of the clockwork mechanism through shaft 60 and gearing 61.

The drawing shows the cardholder in normal position and locked against lateral shifting and forward movements and shows the feeler 29 in a time set position. The feeler 29 is adjusted to different positions from the clockwork mechanism through slide 34 and rod 35. The holder is shifted laterally by the clockwork mechanism through rod 27 and release bar 26 and the action of crank arm 1. In the operation of the machine for marking a card the workman inserts the card down into the cardholder through the mouthpiece 3 until the card bears on the feeler 29 and forces it down. This action releases the latch 32, allowing the cardholder to be swung forward to printing position by engagement of the hand of the workman holding the card with the mouthpiece. The forward movement of the cardholder releases latch 18 so that the hammer 12, 13 will be impelled for printing action by spring 16 supplemented initially by spring 20. On the withdrawal of the card and release of the cardholder from the hand, the cardholder is returned to normal position by spring 19, the feeler and striker are reset for a subsequent operation and latch 18 re-engaged with bar 17 and the springs 16 and 20 retensioned. If, during an in-checking period, a workman has to go out of the factory and has to check his outgoing time, he inserts his card and moves the cardholder backward from its normal position against resistance of springs 16 and 20. This action releases latch 23, allowing the cardholder to be laterally shifted as required, after which the workman moves the cardholder forward for a card printing operation.

Upon the release of the cardholder the parts will be automatically returned to normal position, as previously explained.

From the foregoing description, taken in connection with the drawing, the construction and mode of operation of my improved time recorder will be readily understood without a further and extended description, and it will be seen that the invention provides a construction whereby the working operations may be carried out by one hand of the operator through movements of the cardholder and its supporting shaft, thus doing away with the use of auxiliary operating means for the purpose. Also it will be seen that the construction described provides a machine of simplified construction as compared with other machines in which the cardholder is operated for printing operations.

Conceivably the cardholder may be operated by other angular movements relative to the shaft, and it is to be understood that in this and other respects I do not desire to be limited to the exact details of construction shown and described, for obvious modifications will occur to a person skilled in the art.

Having thus described my invention, I claim:

1. In a workman's time recorder, a time controlled printing mechanism, a movable card holder, detent means operating on the card holder and releasable by insertion of a card in the card holder, and means actuated by movement of the card holder for operating the printing mechanism.

2. A workman's time recorder according to claim 1 in which the movable card holder is rockably mounted and movement in one direction effects a printing operation and rocking in the other direction permits lateral shifting of the cardholder.

3. In a workman's time recorder, a printing mechanism including a movable printing member, a rock shaft, a cardholder mounted to rock with said shaft between normal and printing positions, means for locking the shaft from forward motion and releasing the same by a card inserted in the holder, and a latch engageable with the printing member to hold the same from action when the holder is in normal position and operative to release said printing member when the holder is moved to printing position.

4. In a workman's time recorder, a rockable shaft, printing means, a cardholder laterally shiftable longitudinally on the shaft to different printing positions and rockable with the shaft to energize the printing means, means for normally holding the printing mechanism inoperative and the cardholder from printing movement, and means actuated by insertion of a card in the holder for releasing the cardholder for movement to printing position and on such movement of the cardholder releasing the printing mechanism for a printing action.

5. In a workman's time recorder, a rock shaft, a cardholder shiftable laterally on the shaft and rockable therewith forwardly and rearwardly from a normal position, time controlled means for laterally shifting the holder, a time controlled latch device for securing the holder in laterally shifted positions for in and out recordings, a printing mechanism including a printing element, spring means tensioned by rocking movements of the holder for impelling the printing element and yieldingly holding the holder from rearward movement beyond its normal position, a latch device acting on the shaft for holding the

holder and shaft from forward movement, a latch device for holding the printing mechanism from action and adapted to be released when the holder and shaft are rocked in a forward direction, a member movable when a card is inserted in the holder to release the second named latch device, and means operative on a backward rocking movement of the holder for releasing the first named latch device independently of its time controlled means to permit of a manual lateral shift of the cardholder.

6. In a workman's time recorder, a rock shaft, a cardholder rockable therewith from a normal position to a printing position, a printing mechanism including a printing element, spring means tensioned by movements of the cardholder from its printing position to its normal position for impelling the printing element when the holder is subsequently moved from its normal position to its printing position, a latch device acting on the shaft for holding the cardholder from movement to printing position, a latch device for holding the printing element from action and adapted to be released when the cardholder is moved to printing position, and a member movable by a card inserted in the cardholder to release the first named latch device.

7. In a workman's time recorder, a printing mechanism, a laterally shiftable cardholder pivotally movable backwardly and forwardly from a normal position, means for normally holding the cardholder from lateral shifting movements and releasing the same for such movements when the cardholder is pivotally moved backwardly from its normal position, means operative on a movement of the cardholder from its normal position to a rearward position for rendering the printing mechanism active for a printing action, means for normally holding and biasing the cardholder from forward and backward movements respectively and for normally holding the printing mechanism from a printing action, and means operative by the insertion of a card in the cardholder to release the second named holding means to adapt the cardholder and printing mechanism to be operated for a printing action.

8. In a workman's time recorder, a printing mechanism, a cardholder mounted for lateral shifting movements to different printing positions and for rocking movements about an axis in a direction at right angles to its lateral movements for effecting actuation of the printing mechanism, and locking and biasing means for normally holding the cardholder from forward and backward rocking movement effective to print and the printing mechanism from actuation and released by the insertion of a card in the card holder to permit rocking movement of the cardholder and actuation of the printing mechanism.

9. In a workman's time recorder, a printing mechanism, a laterally shiftable cardholder pivotally movable in opposite directions from a normal position for printing actions, means for normally holding the cardholder from lateral shifting movements and releasing the same for such movements when the cardholder is pivotally moved in one direction for a printing action, means for normally holding and biasing the cardholder from forward and backward movement and for normally holding the printing mechanism from a printing action, and means actuated by the insertion of a card in the holder to release the same for movement in either direction and rendering the printing mechanism active for a printing action.

10. In a workman's time recorder, a printing mechanism, a laterally shiftable, pivotally movable cardholder manually movable in opposite directions from a normal position, means for normally holding the cardholder from lateral shifting movements and releasing the same for a manual lateral shift when the cardholder is pivotally moved in one direction from its normal position, means for normally holding and biasing the cardholder from forward and backward pivotal movement, and means operative on the insertion of a card in the holder to permit pivotal movement of the holder in either direction from its normal position and means for actuating the printing mechanism by pivotal movement of the holder in one direction.

11. In a workman's time recorder, a cardholder movable from a normal position to a printing position, a printing mechanism including a printing element, spring means tensioned on a 20 return movement of the cardholder from its printing position to its normal position for ac-

5 tuating the printing element, a latch device for holding the cardholder from printing movement, a latch device for holding the printing element from action and adapted to be released when the cardholder is moved to printing position, and a member operable by a card inserted in the cardholder to release the first named latch device.
